ALBERT H. VANDAM, OF NEW YORK, N. Y., ASSIGNOR TO TURNER & VANDAM, OF NEW YORK, N. Y., A CORPORATION OF NEW YORK.

WASHABLE FABRIC.

Application filed August 8, 1927. Serial No. 211,533.

The present invention is concerned with the provision of a washable fabric in which suitable printed patterns are accentuated or supplemented by shadow effects on the fabric body or background.

The invention is particularly concerned with the provision of a washable fabric suitable for use as a shirting or pajama material.

10 Objects of the invention are to provide a new fabric which permits the production of a number of unique and attractive designs by virtue of the special arrangement of white background, printed colored pattern, and the 15 shadow design on the background which tends to set off the pattern.

Another object of the invention is to provide an unusual and attractive shirting fabric of this character which may be manufactured with comparative economy, and which may withstand numerous washings without fading of either the colored pattern or the shadow background.

With the above noted and other objects in view, the invention consists in certain novel features of construction and combinations and arrangement of parts, as will be more fully hereinafter set forth and pointed out in the claims. The invention may be more 30 fully understood from the following description in connection with the accompanying drawings, wherein—

The drawing is a fragmentary plan view of a piece of fabric embodying the invention and showing one repeat of a design.

In the drawing I have used the reference character 10 to designate the fabric body which may be of cotton, silk, or cotton and silk combinations, such as are commonly used 40 for shirting and pajama fabrics. The fabric is of such a nature that it is ordinarily lustrous, even when washed. The shadow background effects are produced by printing the fabric with a suitable gloss or lustering 45 removing agent, preferably combined with a tint. As illustrated in the drawing the shadow design consists of a solid square 11 arranged within a concentric hollow square 12.

The agent used for printing the fabric to

produce the shadow background is preferably zinc oxide with which is combined a tint in the nature of a fast dye. The tint is preferably one which varies the original fabric color only slightly, so that the addition of the tint together with the removal 55 of the gloss or luster by the oxide, results in the production of a phantom or shadow effect. The use of the fast dye is of course to prevent damaging of the shadow design by 60 washing.

A printed and colored pattern such for instance as the diamonds or squares 13 is also applied to the fabric. In this particular instance the printed squares 13 are superimposed on the solid squares 11 of the shadow 65 design. It is to be understood however, that the particular design illustrated forms no part of the invention, and that an infinite variety of shadow designs on color printed 70 designs might be employed. For instance, colored stripes might be used in connection with any appropriate shadow design, the invention being in no way limited in this respect. It will be noted that in the finished 75 fabric the printed design is augmented, and in some instances accentuated by the shadow effect behind it, and a tremendous variety of extremely attractive designs may be thus produced.

Obviously, various changes and alterations 80 might be made in the general form and arrangement of the parts described without departing from the invention. Hence I do not wish to limit myself to the details set forth, but shall consider myself at liberty to make 85 such changes and alterations as fairly fall within the spirit and scope of the appended claims.

I claim:

1. A washable fabric including a flat colored glossy background, a shadow design on the background consisting of design areas printed with a gloss removing agent tinted with a fast dye of a shade but slightly different from the background color, and a colored design overlying the shadow design.

2. A washable woven fabric including a glossy white background, a shadow design

on the background consisting of design areas printed with zinc oxide, slightly tinted with a fast dye, and a colored design printed over the shadow design.

5. 3. A method of producing fabrics which includes the step of printing on a lustrous white background with zinc oxide containing

a fast dye to produce a lusterless shadow design which contrasts only slightly in color with the background.

10

Signed at 66 Worth St., in the county of New York, and State of New York, this 5th day of August, A. D. 1927.

ALBERT H. VANDAM.
